Samuel Godd of Waltham, Massachusetts

Letters Patented

The schedule referred to in these Letters Patented and making part of the same containing a description in the words of the said Samuel Godd himself of his improvement in the Hollow cylinder Flyer for manufacturing roving, yarn and thread to all to whom these presents shall come,

Be it known that I Samuel Godd of Waltham in the County of Middlesex and State of Massachusetts have invented a new and useful improvement in the method of manufacturing roving, yarn and thread by the use of the hollow cylindrical flyer which has not heretofore been known or used and that the following is a full and exact description thereof.

The drawing herein annexed numbered 1, represents the machinery used for manufacturing, roving, yarn and thread the parts of the drawing; A. A. represents a perpendicular spindle around which the hollow cylindrical Flyer revolves B. the flyer D. D. the whist, to receive the band, or belt which causes the flyer to revolve C. the part contiguous to the tube called the bushing with which the flyer revolves F. a cylindrical tube, on which the bushing rests likewise the bushing revolves around the tube which passes ^{up} and over of the bushing G. represents the roving, yarn or thread passing down through the roller H. H. and the guides A. A. and also the guides or hook I. on the top of the flyer and around the top sufficient to give the required draft on to the spool C, all. A. represents a stationary rail in which the tube is fixed. L. L. a movable iron to let side and fast the spool C, & H. a weight to keep the spindle in its place. What I claim as my own invention and not previously known in the above machine, see the

14. 9638 X
B. and C. (the flyn and bushing) style of Ladd. Patent hollow
cylindrical flyns, and can be made of wood or metallic sub-
stances, likewise the application of the tube on which the bushing
sets and around which said bushing moves.
